UNITED STATES PATENT OFFICE

154,573

DESIGN FOR A LADY'S HANDBAG

Abraham Walitzky, Lakewood, N. J., assignor to Camey Handbag Co., Inc., Perth Amboy, N. J., a corporation of New York

Application December 6, 1948, Serial No. 150,011

Term of patent 14 years

(Cl. D87—3)

To all whom it may concern:

Be it known that Abraham Walitzky, a citizen of the United States of America, and resident of Lakewood, New Jersey, has invented a new, original, and ornamental Design for Lady's Handbag, of which the following is a specification, reference being had to the accompanying drawing, forming part thereof, in which

Fig. 1 is a front elevational view of a lady's handbag, embodying my new design;

Figs. 2, 3, 4 and 5 are enlarged rear, side, top and bottom views thereof;

Fig. 6 is a top plan view of the bag shown in Fig. 1, but with the uppermost flap opened and turned back;

Fig. 7 is a view similar to Fig. 6 but showing the lowermost flap opened and turned back 180 degrees; and

Fig. 8 is a side elevational view thereof.

I claim:

The ornamental design for a lady's handbag, substantially as shown.

ABRAHAM WALITZKY.
